Primary Examiner — Sandra Snapp*(74) Attorney, Agent, or Firm* — Seed Intellectual Property Law Group LLP**CLAIM**

The ornamental design for a rolling muscle massager, as shown and described.

DESCRIPTION

FIG. 1 is an isometric view of a first embodiment of a rolling muscle massager showing my new design;

FIG. 2 is a front elevation view thereof, the rear elevation, top plan and bottom plan views are identical thereto;

FIG. 3 is a left side elevation view, the right side elevation view being identical thereto;

FIG. 4 is an isometric view of a second embodiment of a rolling muscle massager showing my new design;

FIG. 5 is a front elevation view thereof, the rear elevation, top plan and bottom plan views being identical thereto; and,

FIG. 6 is a left side elevation view, the right side elevation view being identical thereto.
